CLAIM

We claim the ornamental design for a bezel for an entry opening of a litter device for domestic animals, as shown and described.

DESCRIPTION

FIG. 1 is a front perspective view of a litter device for domestic animals with a bezel about the entry opening;

FIG. 2 is a rear perspective view thereof;

FIG. 3 is a front view thereof;

FIG. 4 is a rear view thereof;

FIG. 5 is a left side view thereof;

FIG. 6 is a right view thereof;

FIG. 7 is a top view thereof; and,

FIG. 8 is a bottom view thereof.

The broken lines depict features of the bezel for an entry opening and the litter device for domestic animals that form no part of the design claim.
